SARCOSINATE SHAMPOO

John A. Anderson, Springfield Township, Hamilton County, Ohio, assignor to The Procter & Gamble Company, Cincinnati, Ohio, a corporation of Ohio
No Drawing. Filed Feb. 10, 1960, Ser. No. 7,779
4 Claims. (Cl. 252—153)

This invention relates to a sarcosinate-based shampoo formulated from a combination of ingredients so selected and so proportioned that outstanding lathering, cleaning, hair conditioning and hard water resistance characteristics are obtained.

Most users of shampoos have definite requirements with respect to the performance characteristics of the products they use. A shampoo which merely cleans the hair is not necessarily a satisfactory product; it is often said that a shampoo which cleans too well is unsatisfactory. In addition to cleaning adequately, the product must lather well during the shampooing operations and must condition the hair, i.e. leave the hair in a soft, smooth, lustrous and easily manageable state. The shampoo must be mild and have sufficient resistance to hard water since hard water may cause a reduction in lather and cleaning efficiency and may cause an undesirable film formation on the hair. The use of softened water or special rinses are not satisfactory solutions to hard water problems for a commercially acceptable shampoo.

The chief problem in formulating a shampoo which has the combination of the requisite properties is that a particular ingredient which will impart to the shampoo one or perhaps several of the requisite properties in an outstanding manner will adversely affect one or more of the remaining properties. For example, soap-based shampoos, in soft water, have excellent cleaning, lathering and hair conditioning properties; however, any hardness in water adversely affects the lathering characteristics and leaves the well known undesirable hard water soap curd. Sequestering and curd dispersing additives have improved soap shampoos to some extent but the majority of successful shampoos are based on those non-soap synthetic detergents which lather and clean well in hard or soft water. Such non-soap detergents, however, have the shortcoming of cleaning so well that the natural oil of the hair, which naturally conditions the hair, is removed leaving it harsh and unmanageable.

If the shampoo preparation is designed to preserve much of the natural oil in the hair, the criticism can be voiced that it does an incomplete cleaning job. Some shampoos attempt to solve this problem by using a highly effective detergent with a hair conditioning agent which serves as a replacement for the oil removed from the hair. Examples of such hair conditioning agents are polyglycols, fatty acid esters of glycols, natural or synthetic waxes, and lanolin derivatives. Use of formulations containing excessive amounts of hair conditioning agents of the oily type may cause the hair to have an unpleasant oily appearance and feel. Formulations containing certain hair conditioning agents suffer from the additional difficulty that the oily material inhibits sudsing of the shampoo. Most people have come to expect copious lather from their shampoo and are dissatisfied if it is not formed.

It is an object of this invention to provide a homogeneous shampoo which is preferably substantially clear and which produces a copious lather, effectively cleans the hair, and leaves the hair, after drying, in a soft, lustrous, easily manageable condition.

It is another object of this invention to provide a shampoo which has the above characteristics in hard as well as soft water and which does not form an undesirable hard water precipitate.

2

It was found that these and other objects are obtained by providing a shampoo containing, as its essential ingredients in an aqueous vehicle, an N-acyl sarcosinate, an alkyl sulfate or an alkyl ethoxylated ether sulfate and a blend of acyl mono- and diethanolamides. These ingredients are so selected and so proportioned that a shampoo having a highly satisfactory balance of the requisite properties, enumerated above, is obtained. Minor amounts of a solvent should be included in the shampoo to improve its physical characteristics and minor amounts of a sequestrant can be included, if desired, for the same purpose as hereinafter more fully described. The pH of the shampoo should be in the range of 6 to 7.5 for optimum performance and physical characteristics.

The essential ingredients of the shampoo of this invention are defined in greater detail as follows: N-acyl sarcosinates are the salts of condensation products of fatty acids with sarcosine, $RCON(CH_3)CH_2COOM$; alkyl sulfates are the salts of sulfated fatty alcohols, $R'OSO_3M$; alkyl ethoxylated ether sulfates are mixtures of salts of sulfated condensation products of from 1 to 5 moles of ethylene oxide with one mole of fatty alcohol,

x ranging from 1 to 5 and preferably averaging about 3; acyl monoethanolamides are the condensation products of one mole of fatty acid with one mole of ethanolamine, $RCONHCH_2CH_2OH$; acyl diethanolamides are the condensation products of one mole of fatty acid with two moles of ethanolamine, $RCON(CH_2CH_2OH)_2$.

The acyl radicals (RCO) and alkyl radicals (R') in the above ingredients preferably have a chain length of 12 carbon atoms or are mixtures of radicals ranging in chain length from 10 to 18 carbon atoms such that at least about 45% of the radicals in any given ingredient contain 12 carbon atoms. Suitable mixtures are available from natural or synthetic sources. Coconut oil (or other oil from the coconut oil group, e.g. palm kernel or babassu oil) is a source for coconut type fatty alcohol and coconut type fatty acids which have chain lengths suitable for the ingredients used in the shampoo of this invention. For example the middle cut obtained in the distillation of coconut fatty alcohol having the following composition: 2%— C_{10} , 66%— C_{12} , 23%— C_{14} and 9%— C_{16} alcohols, is a desirable source for alkyl radicals in the above ingredients; coconut fatty acids having the same chain length composition are a desirable source of acyl radicals. Whole cut coconut fatty acids can also be used as a source of acyl radicals; an example of the chain length distribution of such material is C_{6-10} —15%, C_{12} —50%, C_{14} —17%, C_{16} —7% and C_{18} —11%.

The cation M in the above ingredients can be sodium, potassium, ammonium or triethanolammonium. The latter is preferred because of the somewhat greater solubility of the triethanolammonium salts.

The chief ingredient of the shampoos of this invention is acyl sarcosinate. This synthetic detergent has excellent lathering and cleansing characteristics and at the same time has outstanding hair conditioning characteristics. This latter characteristic is a result of a very thin conditioning film of acyl sarcosinate which is formed around each strand of hair after the shampooing operation and during rinsing. This film is similar to the thin conditioning film formed by soap in soft water. However, the sarcosinate conditioning film formed around the hair-strands in hard water shampooing is just as satisfactory as that formed in soft water whereas hard water soap film is highly undesirable.

Although the acyl sarcosinate lathers well and cleans well, it was found that it should be supplemented by an alkyl sulfate or an alkyl ethoxylated ether sulfate in cer-

tain proportions in order to provide, in the shampoo, a mixture of components which provides the large amount of lather which is desired by the user. These sulfated detergents by themselves do not have the outstanding conditioning properties of the acyl sarcosinate.

The acyl sarcosinate is used in the amount of about 6% to about 15% of the shampoo composition. (All percentages and ratios used herein are by weight.) The sulfated detergent is used in the amount of about 2% to about 8% of the shampoo composition. Since the acyl sarcosinate should predominate in order to obtain the desired hair conditioning characteristics, the ratio of sarcosinate to sulfated detergent should be in the range of about 3:2 to about 3:1. The above percentages are fixed on the lower side to provide the user with a sufficient amount of detergent for satisfactory results with respect to the volume of detergent solution customarily used in shampooing. They are fixed on the upper side by solubility of the various ingredients in the shampoo formulation which should not be exceeded if a substantially clear homogeneous product is to be obtained and maintained at ordinary temperatures.

Although the acyl sarcosinate and sulfated detergent ingredients in the proportions described above provide excellent lathering characteristics, the shampoo, without certain additional lather builders does not have the particular lathering characteristics required by the user. Lather is important to the shampoo user because he or she uses it as a measure of the correct amount of shampoo needed to wash the hair thereby avoiding both insufficient cleaning and wasted product. Moreover, shampoo users have come to associate lather with detergent efficiency. The shampoo user desires a large amount of lather which is stable (persists throughout the shampooing operation) and which has good texture, i.e. body and lubricity. While the mixture of acyl sarcosinate and sulfated detergent provides an ample volume of lather, lather builders should be used with the mixture to increase the stability of and improve the texture of the lather.

Acyl monoethanolamides are outstanding lather builders for the mixture of sarcosinate and sulfated detergent described above but their use as the sole builders detracts undesirably from the hair conditioning properties of the acyl sarcosinate. Moreover, the solubility of the acyl monoethanolamide is somewhat limited making it more difficult to obtain a homogeneous product than if the more soluble acyl diethanolamides are used. Acyl diethanolamides have limited lather building properties and do not detract from the hair conditioning properties of the acyl sarcosinate; however acyl diethanolamides do not provide a satisfactory lather building action for the mixture of acyl sarcosinate and sulfated detergent. Thus the use of either an acyl monoethanolamide or an acyl diethanolamide as the sole lather builder provides unsatisfactory characteristics in either hair conditioning or lathering of the resultant shampoo.

Surprisingly, it was found that a careful blend of acyl mono- and di-ethanolamides used in conjunction with the combination of acyl sarcosinate and sulfated detergent described above provides a homogeneous shampoo having outstanding lathering, cleaning and hair conditioning characteristics in either hard or soft water. It was found that the ratio of the acyl monoethanolamide to the acyl diethanolamide should be in the range of about 2:1 to about 1:2 and the total amount of the two amides should be from about 3% to about 8% of the shampoo composition.

In order to ensure that the shampoo composition containing the above essential ingredients is homogeneous and remains so, a solvent, either ethanol, glycerin or propylene glycol, should be included in the shampoo. The solvent also acts to maintain the clarity of the preferred substantially clear shampoo product. The solvent is especially desirable to ensure that the shampoo formulation will recover to a substantially clear homogeneous product

after being rendered non homogeneous and/or cloudy at low temperatures which might be encountered in storage or transit. The ethanol, glycerin or propylene glycol is used in an amount of about 3% to about 12% of the shampoo composition. Solvents other than ethanol, glycerin or propylene glycol, such as methanol, isopropanol, or ethylene glycol, are not satisfactory because of toxicity and/or odor problems. Ethanol is the preferred solvent.

It is preferable to include in the shampoo compositions of this invention a sequestrant to ensure that the solution of ingredients is as clear as possible. To this end about 0.3% to about 2% of an amino polycarboxylate sequestrant is included. Examples of this type of sequestrant are ethylene diamine tetra acetates, hydroxyethyl ethylene diamine triacetates, nitrilo triacetates, 2 hydroxyethyl imino diacetates, diethylenetriamine penta acetates, and 1,2 diamino cyclohexane tetra acetates. These sequestrants are used in the form of their full or partial sodium, potassium, ammonium or triethanolammonium salts so as to conform with the pH range of the shampoo as hereinafter discussed. The exact form of the sequestrant will depend on the particular compound and cation used. Sequestrants also tend to increase the volume of lather of the shampoo. Ethylene diamine tetra acetate is the preferred sequestrant.

The pH of the shampoo should be in the range of about 6 to about 7.5. At pH's less than about 6 the clarity of the shampoo tends to be impaired. At pH's greater than about 7.5 the lathering characteristics of the shampoo are reduced. The pH of the shampoo can be adjusted if necessary with any of the usual acidic or basic agents such as citric acid or triethanolamine.

Various minor ingredients customarily used in shampoos can be added to the composition of the invention to make it more attractive in appearance or use, but are not necessary. Examples of such minor ingredients are: up to about 0.5% color; up to about 2% thickening agent such as methyl cellulose or sodium carboxymethylcellulose; up to about 1% perfume; up to about 0.5% of a color stabilizer such as ammonium or sodium sulfite; up to about 0.01% of a preservative such as phenyl mercuric acetate; up to about 0.2% of an ultraviolet absorbent or an antioxidant. Although the shampoo compositions of this invention preferably are substantially clear, up to about 5% of an opacifier, such as ethylene glycoldistearate, can be added if an opaque product is desired.

The shampoo of this invention is illustrated by the following example.

Example

A shampoo composition was obtained by uniformly mixing together the following ingredients:

4% triethanolamine salt of the sulfated condensation product of 3 moles of ethylene oxide and one mole of coconut oil fatty alcohol having the following chain length distribution: 2% C₁₀, 66% C₁₂, 23% C₁₄ and 9% C₁₆
 55 10% triethanolamine N-acyl sarcosinate, the acyl radicals being derived from coconut oil fatty acids and having the following chain length distribution: 10% C₈₋₁₀, 48% C₁₂, 21% C₁₄, 10% C₁₆ and 11% C₁₈
 3% monoethanolamine of coconut oil fatty acids having the following chain length distribution: 16% C₆₋₁₀, 48% C₁₂, 17% C₁₄, 9% C₁₆ and 10% C₁₈
 65 3% diethanolamide of coconut oil fatty acids having the following chain length distribution: 16% C₆₋₁₀, 48% C₁₂, 1% C₁₄, 9% C₁₆ and 10% C₁₈
 0.65% ethylenediamine tetraacetic acid (as its partial triethanolammonium salt)
 70 7% ethanol
 0.75% methyl cellulose, a 2% solution of which has a viscosity of 4000 cps. at 68° F. and a gel point of 140° F.
 0.15% sodium sulfite
 75 0.007% phenyl mercuric acetate

0.75% perfume
Balance water.

The pH of the shampoo was 6.7.

The shampoo was a clear, white, homogeneous liquid. When used on unclean human hair with both hard and soft water, copious lather having a good texture quickly formed and persisted during the shampooing operation. There was no evidence of any adverse effects with the use of hard water, even that having a hardness of 12 grains per gallon. The product and its lather rinsed easily and substantially completely away leaving the hair, after drying, in a soft, lustrous state which was easy to comb and manage. In the opinion of a number of experienced beauticians who performed the shampooing operation with the composition of this example, and a number of persons whose hair had been shampooed with the composition, the hair conditioning properties of the shampoo were excellent and were at least equal to the conditioning properties of a high quality soft-water soap shampoo.

Propylene glycol or glycerin can be substituted in an equal amount for ethanol in the above example with substantially equal results.

The sodium, potassium or ammonium salts of the sulfated condensation product and of the N-acyl sarcosinate described in the above example can be substituted in equivalent amounts for the corresponding triethanolamine salts used in the composition of the example with substantially equal results.

An equivalent amount of triethanolamine, sodium, ammonium or potassium lauryl sulfate can be substituted for the sulfated condensation product in the above example with substantially equal results. Alkyl ethoxylated ether sulfates are preferred over the corresponding alkyl sulfates because the former have slightly greater solubility and greater mildness.

An equivalent amount of a triethanolamine or sodium salt of hydroxyethyl ethylene diamine triacetic acid or nitrilo triacetic acid can be substituted for the ethylene diamine tetra acetic acid in the above example with substantially equal results.

What is claimed is:

1. A clear homogeneous, liquid shampoo which will produce copious stable lather having good texture; effectively clean the hair; and leave the hair in a soft, lustrous, easily manageable condition even when used in hard water, consisting essentially of an aqueous solution of (a) about 6% to about 15% of an N-acyl sarcosinate, (b) about 2% to about 8% of a non-soap detergent selected from the group consisting of alkyl sulfates and alkyl ethoxylated ether sulfates containing one to five ethylene oxide units per molecule, (c) about 3% to about 8% of a mixture of an acyl monoethanolamide and an acyl diethanolamide, the ratio of said amides being in the range of about 2:1 to about 1:2, (d) about 3% to about 12% of a solvent selected from the group consisting of ethanol, glycerin and propylene glycol, the ratio of (a) to (b) being in the range of about 3:2 to about 3:1, the acyl and alkyl groups in the ingredients ranging from 10 to 18 carbon atoms in chain length with at least 45% of the said groups in each ingredient being 12 carbon atoms in chain length, the cations of the said sarcosinate and the said detergent being selected from the group consisting of sodium, potassium, ammonium and triethanolam-

monium, the pH of said solution being from about 6 to about 7.5, the percentages and ratios being by weight.

2. The shampoo composition of claim 1 which includes as an additional ingredient about 0.3% to about 2% of an amino polycarboxylate sequestrant selected from the group consisting of ethylene diamine tetraacetates, hydroxy ethyl ethylene diamine triacetates, nitrilo triacetates, 2 hydroxyethyl imino diacetates, diethylenetriamine penta acetates and 1,2 diamino cyclohexane tetra acetates.

3. A clear, homogeneous, liquid shampoo which will produce copious stable lather having good texture; effectively clean the hair; and leave the hair in a soft, lustrous, easily manageable condition even when used in hard water, consisting essentially of an aqueous solution of (a) about

15 6% to about 15% of a triethanolamine N-acyl sarcosinate, (b) about 2% to about 8% of triethanolamine alkyl ethoxylated ether sulfates containing an average of three ethylene oxide units per molecule, (c) about 3% to about 8% of a mixture of an acyl monoethanolamide and an acyl diethanolamide, the ratio of said amides being

20 in the range of about 2:1 to about 1:2, (d) about 3% to about 12% ethanol, (e) about 0.3% to about 2% of an ethylenediamine tetra acetate, the ratio of (a) to (b) being in the range of about 3:2 to about 3:1, the acyl and alkyl groups in the ingredients ranging from 10 to 18 carbon atoms in chain length with at least 45% of the said groups in each ingredient being 12 carbon atoms in chain length, the pH of said solution being from 6 to 7.5, the percentages and ratios being by weight.

25 4. A clear, homogeneous, liquid shampoo which will produce copious stable lather having good texture; effectively clean the hair; and leave the hair in a soft, lustrous, easily manageable condition even when used in hard water, consisting essentially of an aqueous solution of about

30 10% of a triethanolamine N-acyl sarcosinate, about 4% of triethanolamine alkyl ethoxylated ether sulfates containing an average of three ethylene oxide units per molecule, about 3% of an acyl monoethanolamide, about 3% of an acyl diethanolamide, about 0.65% of triethanol-

35 amine ethylene diamine tetraacetate, about 7% ethanol, the acyl and alkyl groups in the ingredients ranging from 10 to 18 carbon atoms in chain length with at least 45% of the said groups in each ingredient being 12 carbon atoms in chain length, said solution having a pH of about

40 45 6.7, said percentages being by weight.
